UNITED STATES PATENT OFFICE

106,442

DESIGN FOR A DISPLAY-FORM STAND

Henry Janssen, Wyomissing, Pa., assignor to Textile Machine Works, Wyomissing, Pa., a corporation of Pennsylvania

Application May 14, 1936, Serial No. 62,623

Term of patent 14 years

To all whom it may concern:

Be it known that I, Henry Janssen, a citizen of the United States of America, residing at Wyomissing, in the county of Berks and State of Pennsylvania, have invented a new, original, and ornamental Design for a Display-Form Stand, of which the following is a specification, reference being had to the accompanying drawings forming part thereof.

Fig. 1 is a top plan view of a display-form stand showing my new design;

Fig. 2 is a side elevational view of the stand shown in Fig. 1;

Fig. 3 is a front elevational view of the stand shown in Fig. 1; and

Fig. 4 is a perspective view of the stand shown in Fig. 1.

I claim:

The ornamental design for a display-form stand, substantially as shown.
